UNITED STATES PATENT OFFICE.

MELVIN L. STONE, OF HOPEDALE, MASSACHUSETTS, ASSIGNOR TO DRAPER COMPANY, OF HOPEDALE, MASSACHUSETTS, A CORPORATION OF MAINE.

FILLING-END CONTROLLER FOR LOOMS.

1,115,983.

Specification of Letters Patent.

Patented Nov. 3, 1914.

Application filed February 28, 1914. Serial No. 821,638.

To all whom it may concern:

Be it known that I, MELVIN L. STONE, a citizen of the United States, residing at Hopedale, county of Worcester, and State of Massachusetts, have invented an Improvement in Filling-End Controllers for Looms, of which the following description, in connection with the accompanying drawings, is a specification, like characters on the drawings representing like parts.

The invention to be hereinafter described relates to filling replenishing looms, wherein a fresh supply of filling is automatically provided when that in the running shuttle 15 has become broken or substantially exhausted, and more particularly it has reference to means for controlling the filling end. Looms of this general type are well understood by those familiar with the art, and consequently 20 need not be particularly described herein except in so far as the operation of the replenishing mechanism contributes to the results sought by the present invention. In looms of this character the free ends of the 25 filling leading from the filled bobbin or carrier are secured at a fixed point, so that when the shuttle is picked following filling replenishment the filling will be laid in the shed. When the filling carrier or bobbin is 30 transferred into service relation with the weaving instrumentalities, whether by changing shuttles or placing a filled bobbin in the shuttle in use, the filling end is liable to be broken before it can respond to the sudden 35 strain incident to transfer by unwinding from the bobbin, and should slack exist in the filling end as the shuttle is picked following filling replenishment, the sudden jerk of taking up such slack is liable to cause similar 40 trouble. Whether either of these conditions occur or not, there still remains the further danger that the filling end may be carried into the shed, with the result that imperfect cloth will be woven.

With these facts in view, the aims and purposes of the present invention are to provide a filling end controlling means such that any or all of these objectionable conditions shall be eliminated, as will more fully appear 50 from the following description and accompanying drawings of one form of means for carrying the invention into practical effect, it being understood that the invention is not limited to the particulars shown and de-

scribed, but, in its true scope, is defined by 55 the claims.

In the drawings:—Figure 1 is an end view looking toward the filling replenishing mechanism at the replenishing side of the loom, and showing one form of the present 60 invention, the shuttle-box being in section; and Fig. 2 is a side view of the parts illustrated by Fig. 1, showing certain portions in section, and the end controller in the various 65 positions it may assume, the shuttle-box being omitted for clearness.

In the illustrated form of the invention it is assumed as associated with a filling replenishing loom of the type wherein replenishment is effected by a change of the filling 70 carrier or bobbin in the shuttle rather than by a change of the shuttle itself, but it is to be understood that the invention is not restricted in this respect. Looms of this general character are provided with a source of 75 supply of filled carriers or bobbins, and as the filling in the service shuttle becomes practically exhausted or broken, or for other reasons the filling therein is no longer desired, these filled carriers or bobbins are successively taken from the source of supply 80 and made to replace the carrier or bobbin in the shuttle. In the form or embodiment of the invention shown the source of supply is provided by a rotatable hopper or feeder, 85 and the present invention is well adapted for use in connection therewith; but it is not the intention to restrict the invention in this respect, as it may adapt itself in the hands of one familiar with the art to other forms 90 of hoppers or means for supplying filled carriers or bobbins.

In the drawings the lay 1, only a portion 95 of which is shown, may be of usual character, and is provided with the shuttle-box 2 having an opening 3 for the discharge of the carriers or bobbins as they are ejected from the shuttle 4. The picker 5 and picker stick 6 may be of usual construction and operation for throwing the shuttle across 100 the lay.

Mounted upon a fixed part of the loom frame by suitable securing means, such, for instance, as the bracket 7, is the filling feeder 8 which may be of any suitable character for 105 holding a supply of filled carriers or bobbins. In the present illustration the feeder 8 is shown as comprising the two disks 9 and 10

between which a series of filled carriers or bobbins may be supported, one of said carriers or bobbins being shown at 11, Fig. 2, and a series of them being indicated by 5 dotted lines in Fig. 1. The said disks 9 and 10 rotate in unison on the supporting shaft 12 and to this end may be connected by sleeved hubs 13 and 14 and set screw 15, or any other suitable means may be employed.

10 Mounted for rotative movement with the feeder are a series of filling end controllers, preferably one for each filling carrier or bobbin. These filling end controllers are preferably formed elastic and are adapted 15 to engage the filling end between the ends of the filling carriers or bobbins and the filling end holder, as will hereinafter more fully appear; and associated with the filling end controllers there is means to limit or 20 restrict the action of the filling end controllers upon the filling ends, until the filling end controllers reach a predetermined position, whereupon they become free to act upon their respective filling ends. As a 25 good practical form of this feature of the invention, there is mounted for rotative movement with the feeder 8, a plate or disk 16 which may be secured for rotative movement with the feeder by means of an appropriate set screw 17, or otherwise. Projecting 30 from the central portion of the disk 16 is a filling end holder 18.

Mounted upon the disk 16 are a series of filling end holders 19 which may be formed 35 as spring arms and mounted upon supporting studs 20. A convenient form of such controllers is indicated in Fig. 1, wherein the arm 19 has its end portion 21 formed with an elongated bearing portion over 40 which the end of the filling a extending from the carrier 11 to the filling end holder 18 may pass. The arm 19 at its other end may be turned into the form of a spring 22 about the stud 20, the free end 23 of the 45 spring bearing upon the face of the disk 16, the construction being such that the filling end controllers will have their respective end portions 21 positioned for engagement with a filling end between the filling carrier 50 and the filling end holder, and will normally tend to draw or pull upon the filling end when free to act.

As hereinbefore indicated, the filling is likely to be broken at the moment of transfer, but a small amount of slack in the filling end or a little elastic action thereon which will readily yield to any pull upon the filling, will overcome the tendency to break at this time. Therefore, the present invention 55 contemplates means which will permit the filling end controllers to act yieldingly and to a limited extent upon the filling end until at or following the moment of transfer, whereupon the filling end controllers are 60 permitted freedom of action to take up any slack in the filling that may exist before the shuttle is picked, and to act thereafter to withdraw or snap the filling end away from the weaving instrumentalities when it is parted at the selvage of the cloth so that it 65 will not be carried into the shed. As one means to the above end, the filling end controllers have a guard overlying a portion of said controllers, so that said controllers may normally bear upon the surface of the guard 70 while the feeder and filling end controllers are rotated to move the carriers or bobbins toward the point of transfer. In the illustrated form of the invention, this guard 75 comprises a circular plate 24 having an arm 25 which may be appropriately secured to the stud 26 by suitable means such as the nut 27 or other form of securing means, Fig. 1. This guard 24 extends about the disk 16 substantially as indicated in Fig. 1, and 80 overlies the arms 19 of the controllers within the end portions 21 thereof, the construction being such that as the feeder and perforce the disk 16, rotate and carry the filling carriers or bobbins and the filling end controllers in the direction of the arrow indicated in Fig. 1, the filling end controllers will be permitted to act upon the filling ends only to a limited extent defined by the distance between the guard 24 and the face of 85 the disk 16, and will furnish a yielding tension means for giving up sufficient filling for the transfer without danger of breaking the filling end, provided sufficient slack is not already presented. As soon as the filling 90 carrier or bobbin has been transferred and before the shuttle is picked, it is desirable that all slack in the filling shall be taken up to prevent the sudden jerk that would otherwise occur as the shuttle is picked; and the 95 present invention contemplates means to this end as will now be described.

Mounted upon the stud 26 is the trans- 100 ferrer arm 28 carrying at its end the trans- 105 ferrer 29 and normally under the action of a spring 30, as indicated in Fig. 1, the downward movement of the trans- 110 ferrer being effected as usual in this type of machines by an arm 31 which, at the moment of trans- 115 fer, is operated by a suitable bunter, as will be readily understood by those skilled in the art, and as set forth in the patent to Draper and Stimpson, No. 695,040, March 11, 1902. This action of the trans- 120 ferrer for moving the carrier or bobbin from the feeder to the shuttle may be of any usual or desired type.

Pivotedly mounted at 32 on the trans- 125 ferrer arm 28 is a pawl carrier 33 having a lug or toe 34 adapted to engage with the teeth of the ratchet wheel 35 secured to the rotatable feeder 8, the construction being such that upon downward movement of the trans- 130 ferrer the feeder will remain stationary, but as the trans- 135 ferrer is raised under the action of its spring 30, or other means, 130

the feeder and, perforce, the disk 16 will be rotated to bring a fresh bobbin into the position for transfer.

The guard 24 has an escape opening for 5 the filling end controllers, such that as the feeder and disk 16 are rotated on the upward movement of the transerrer to bring a fresh filling carrier or bobbin into position for transfer said guard will permit the 10 filling end controller acting upon the filling end of the carrier just transferred, to assert its elastic force upon the filling end, and take up any slack therein. This escape feature of the guard 24 is provided by the end 15 portion 36 which terminates, as indicated in Fig. 1, at such predetermined point in the rotative movement of the filling end controllers, that said controllers successively escape therefrom immediately following the 20 transfer, substantially as indicated in Fig. 1, thereby taking up the slack in the filling end before the shuttle is picked. The described action of the filling end controllers at this time is indicated at *b*, Fig. 2, and it 25 will be noted that the filling end extending from the shuttle 4 to the filling end holder 18 is now held taut, ready for the pick. After the shuttle is picked and the filling has been properly laid in the shed, it is 30 parted adjacent the selvage of the cloth, as usual in this class of machines, and the controller still acting yieldingly upon the filling end, withdraws or snaps the filling end from danger of being engaged by the shuttle 35 and carried into the shed, as indicated diagrammatically by the position of the controllers at *c*, Fig. 1.

In order to return the filling end controllers to their original or initial position, 40 as hereinbefore described, means are provided for engaging the controllers as the feeder and disk 16 are further rotated to depress the controllers from the position assumed by them as they withdrew the filling end from danger of being carried into the shed. As one form of means to this end, the guard 24 is provided with a returning arm 37, Fig. 1, having a cam or inclined surface as indicated in Fig. 1, and adapted 45 to engage the arms 19 of the controllers as they pass toward it to depress said arms into their initial position.

While the guard 24 has been described as a good, practical form of carrying the invention into effect, it is to be understood 55 that the invention is not restricted thereto, nor to the particular means employed for returning the controllers to initial position, because other forms of mechanism for limiting, freeing, and returning the controllers 60 may readily suggest themselves to those skilled in the art, and the present invention is generic in this respect.

What is claimed is:—

65 1. In a filling replenishing loom, the combination of a filling end controller to engage the filling leading from a filling carrier, and means to limit the slack take-up action of the controller until filling replenishment and thereafter permit further action of the 70 controller to draw upon the filling and remove the filling end from the weaving instrumentalities after it is parted.

2. In a filling replenishing loom, the combination of a filling end holder, an elastic 75 filling end controller adapted to engage a filling end between the filling carrier and filling end holder, and means for limiting the action of the filling end controller until it reaches a predetermined position and then 80 freeing it to exert its elastic action on the filling end.

3. In a filling replenishing loom, the combination of a filling end holder, an elastic 85 filling end controller adapted to engage the filling end between the filling carrier and filling end holder, means for limiting the action of the filling end controller until filling replenishment and then permitting the controller to further act upon the filling end. 90

4. In a filling replenishing loom, the combination of a filling end holder to which the free end of the filling is secured, an elastic filling end controller normally engaging the filling end between the holder and filling carrier, means for limiting the action of the controller upon the filling end until said controller reaches a predetermined position, and mechanism for moving the controller to said position. 100

5. In a filling replenishing loom, the combination of a rotatable feeder to contain a series of filling carriers, a filling end holder, an elastic filling end controller to engage a filling end between a filling carrier and said 105 holder, means for limiting the action of the filling end controller upon the filling end, and means for relatively moving the filling end controller and said first-named means to free the filling end controller and permit it to further act upon the filling end. 110

6. In a filling replenishing loom, the combination of a rotatable feeder to contain a series of filling carriers, a filling end holder, a series of elastic filling end controllers 115 adapted to engage the filling ends between the carriers and holder and movable with the feeder, means for limiting the action of the elastic controllers upon the filling ends, said means freeing the elastic filling 120 end holders successively from its control as they move into a predetermined position.

7. In a filling replenishing loom, the combination of a filling end holder, an elastic filling end controller adapted to engage the 125 filling end between a carrier and the holder and yieldable in one direction in response to any strain upon the filling end, means for limiting the action of the controller in the opposite direction and freeing it to move- 130

ment in said direction when it has reached a predetermined position.

8. In a filling-replenishing loom, the combination of a rotatable feeder for containing a series of filling carriers, a filling end holder, a series of elastic filling end controllers adapted to engage the filling ends between the carriers and said holder, a guard for limiting the elastic action of the series of end controllers and having an escape portion at a predetermined point, and means for moving the elastic filling end controllers successively to said predetermined point to free them from the guard.
15. 9. In a filling-replenishing loom, the combination of a filling end holder, an elastic filling end controller adapted to engage a filling end between the filling carrier and filling end holder, means for limiting the action of the filling end controller until it reaches a predetermined position and then freeing it to exert its elastic action on the filling end, and means to return the filling end controller to the action of said limiting means.

10. In a filling-replenishing loom, the combination of a filling end holder, a filling end controller for acting upon the filling between a carrier or bobbin and the filling end holder, means for restraining the action of the filling end controller until after filling replenishment and freeing the controller before the shuttle is picked.

11. In a filling-replenishing loom, a fill-

ing end holder, a rotatable hopper or feeder, and means rendered operative by rotation of the hopper or feeder after filling replenishment to act upon and take up slack in the filling between the carrier or bobbin and filling end holder.

12. In a filling-replenishing loom, a filling end holder, a rotatable hopper or feeder, means rendered operative by rotation of the hopper or feeder after filling replenishment to draw up the filling between the transferred carrier or bobbin and filling end holder, and means for rendering said first-named means inoperative upon further rotation of the hopper or feeder.

13. In a filling-replenishing loom, the combination of a rotatable feeder, a filling end holder, a series of spring filling end controllers rotatable with the feeder, a guard for restraining the full action of the spring controllers until they reach a predetermined position and then permitting them to act upon the filling between a carrier and the filling end holder, and a cam device for acting upon the spring controllers to return them to the control of said guard.

In testimony whereof, I have signed my name to this specification, in the presence of two subscribing witnesses.

MELVIN L. STONE.
